UNITED STATES PATENT OFFICE.

JAMES H. S. BATES, OF OLYMPIA, WASHINGTON, ASSIGNOR TO UNDERWOOD TYPE-WRITER COMPANY, OF NEW YORK, N. Y., A CORPORATION OF DELAWARE.

TYPEWRITING MACHINE.

Application filed January 29, 1924. Serial No. 689,240.

This invention relates to ribbon-guarding and guiding means for typewriting machines, and particularly to means to prevent the ribbon from fouling with the usual type-bar guide on an Underwood portable front-strike typewriting machine.

At the shifting up of the platen, the lower edge of the ribbon is carried high above the edge of the ribbon guide, and when the ribbon drops to normal position, there is a tendency for it to catch on the type-guide. This is apt to happen when operating rapidly, especially when the platen is dropped before the operator releases the type-key.

To overcome this objection, a shield or guard is secured to the type-guide to extend upwardly to a point beyond the lower edge of the ribbon when the latter is in its extreme top position.

Such guard may be attachable, or it may be made an integral part of the type-guide.

Other features and advantages will hereinafter appear.

In the accompanying drawings,

Figure 1 is a view, in front elevation, of a portion of a portable Underwood typewriter, showing an attachable form of the invention, with the platen in lower-case position and the ribbon in its normal position below the printing line.

Figure 2 is a section taken on the line 2—2 of Figure 1.

Figure 3 is similar to Figure 1, showing the platen in lower-case position and the ribbon positioned for printing in its lower field.

Figure 4 is a view similar to Figures 1 and 3, showing the platen in its upper-case position and the ribbon positioned for printing in its lower field, the lower edge of the ribbon being shown at its highest elevation.

Figure 5 is a perspective view of the form shown in Figures 1 to 4.

Figure 6 shows a modified form of attachable guard.

Figure 7 is a perspective view of one element of the shield shown in Figure 6.

Figure 8 shows upstanding extensions integral with the type-bar guide.

Type-bars 11, each pivoted to a segmental plate 12, strike on a platen 10, on carriage 13 running on front rail 14 and roller-bearing 15 and rear rail 14^a and roller-bearing 15^a. Rails 14 and 14^a and carriage 13 may be dis-

placed upwardly for case-shifting the platen 10 in the usual manner by a mechanism 45, a fragmentary portion thereof being shown in Figure 2. Made fast by screws 16 to segment-plate 12 is a type-bar-guide in the form of a plate 17 having upwardly-extending fingers 18 making a guide 19 for the shoulder 20 on the type-bar. Guide-plate 17 may also be provided with an opening 21 of sufficient width and located so as to enable the typist to clearly see the graduations and numerals on the usual scale 22 therebehind. The lower edge of opening 21 may have an index-pointer 23 centrally thereof and in true alignment with the printing position designated in Figures 1, 3 and 4 as "X". As guide-plate 17 accommodates a part of the printing point indicating means described above, ribbon-supporting arms 37 on a vibrator 30 of a ribbon-vibrating mechanism are necessarily spaced a relatively wide distance apart on each side of the printing point "X". A guide 24 for the ribbon-vibrator may be fastened to rail 14 by screws 25, and may comprise a body-portion 26 and two forwardly-extending portions 27 terminating in upwardly-extending guide-arms 28, which are embraced by clips 29 of the well-known form of ribbon-vibrator 30. To guide the lower end of vibrator 30, a stud 31 projects rearwardly into a slot 32 formed in body-portion 26 of the guide 24. The upper edge of portion 26 adjacent slot 32 engages with cross-bar 33 of the carriage 13 to assist in holding the carriage 13 on the rail 14, as shown in Figure 2.

An inwardly-projecting arm 34 of a vibrating actuating mechanism, not shown, may be connected to headed stud 35 extending forwardly of the ribbon-vibrator 30 (see Figures 1 and 2). Stud 35, in operation, moves upwardly with arm 34 to bring ribbon 36, carried on ribbon-supporting arms 37, to the printing point. Ribbon 36 may be laterally fed between spools, not shown, in the well-known manner. The actuating mechanisms for the ribbon-vibrator 30, spools and feed arrangement for ribbon 36, and the case-shifting means for platen 10 form no detailed part of the present invention, and may be like those in the patent to George W. Campbell, No. 1,370,281, granted March 1, 1921.

When operating typewriting machines having the specific features and arrangement of parts described above or their equivalents at high rates of speed, if, in improper sequence, the platen 10 be shifted from a higher to a lower case position before the type-bar 11 is released, the ribbon 36 will "hang on" the type. This will cause the portion of ribbon 36, between the ribbon-supporting arms 37, over guide-fingers 18 to become slack and curl when the type-bar 11 and the ribbon-vibrator 30 subsequently return to their normal position. This slack in ribbon 36 has a tendency, during the lowering thereof between type-impressions, to catch on guide-fingers 18.

The invention provides a guard or shield 38 to prevent interference between the ribbon 36 and guide-plate 17, which may be of a form that is readily attachable to guide-plate 17 or to other guide-plates of machines already in use. Guard 38 may comprise a body-piece 39, having an upper portion formed into two upstanding spaced wings 40 whose outer sides 41 are forwardly bent to provide smooth edges, and the lower portion of body-piece 39 may be suitably fashioned to provide securing means for fastening to guide-plate 17, as forwardly bent clips 42. For a more permanent form of attachable mounting, shield 38 may be made of two separate parts, each having an upper portion 40^a, similar to wings 40 in the first form described, and a lower portion 39^a may be soldered to the upper part of guide-plate 17 (see Figures 6 and 7).

The ribbon-guard 38, placed to shield the path of the ribbon 36, will eliminate the effect of any possible interference with its normal movements from the cause described or for any other reason that may have the same objectionable tendency.

It is quite obvious that the invention may form a combined type-bar-guiding and ribbon-guarding device, in which the free ends of the guide-fingers 18 are extended upwardly and outwardly to form wings 40^b, as shown in Figure 8.

In the preferred form shown in Figures 1 to 5, it will be noted that the inner edges of the two wings 40 taper from the upper free ends downward to the width of the type-guide, and, as the direct cause of the ribbon catching on the type-guide is a looseness developed in the ribbon-section between the arms 28 of the ribbon-carrier due to the typing action, this looseness, if it manifests itself by bulging forward over the type-guide, will contact with the edges of the wings 40, and, through the tapering of these edges, the bulging ribbon-section will be forced to the rear of said guide and avoid any possibility of catching thereon.

Variations may be resorted to within the scope of the invention, and portions of the

improvements may be used without others. Having thus described my invention, I claim:

1. In a front-stroke typewriting machine, in combination, a ribbon-vibrator to vibrate a ribbon up and down at the printing point, a type-guide in front of the ribbon, and means to prevent interference between the type-guide and the movements of the ribbon during typing, said means including a stationary guard secured to the type-guide in front of the ribbon. 70

2. In a front-strike typewriting machine, in combination, a stationary element, a type-guide on said element, a ribbon-vibrator, and means secured to the stationary element and extending across the printing line close to and on opposite sides of the type-guide, and in front of said vibrator to guard the ribbon from interference in its vibratory movements 85 with the type-guide during typing. 90

3. In a front-strike typewriting machine, the combination of a platen, platen-shifting mechanism, a vibrator for oscillating a ribbon up and down at the printing point of the platen, a stationary element, a type-guide on said element, and means to shield the path of the ribbon and to guard it from being interfered with during its return movement, said means comprising a forked member secured to said stationary element below the printing line, the free ends of said member extending upwardly on opposite sides of the type-guide beyond the lower edge of the ribbon when the latter is in position for typing on its lower field while the platen is held in its upper-case position by the platen-shifting mechanism. 95

4. In a front-strike typewriting machine, in combination, a platen, type-bars carrying types supported to print at a common printing point, a type-bar guide, a vibrator for oscillating a ribbon located between the platen and the type-bar guide, and a guard on said guide to shield the ribbon in its normal movements from interference with the guide. 105

5. In a front-strike typewriting machine, in combination, a platen, type-bars carrying types supported to print at a single printing point, a type-bar guide secured to a fixed part of the machine, a vibrator for oscillating a ribbon located between the platen and the type-bar guide, and a ribbon-guard on said guide to avoid catching the ribbon thereon, said guard extending across the printing line on opposite sides of the printing point in front of the vibrator. 110

6. In a front-strike typewriting machine, in combination, a platen, type-bars carrying types supported to print at a single printing point, a type-bar guide, a vibrator for oscillating a ribbon up and down between the platen and the type-bar guide, a ribbon-guard comprising a forked member secured 125

to said guide below the printing line and having the free ends of said member extending upwardly on opposite sides of the printing point beyond the maximum operative 5 elevated position of the lower edge of the ribbon to prevent the ribbon from catching on said guide.

7. In a front-strike typewriting machine, in combination, a platen mounted for case- 10 shifting, type-bars carrying types supported to print at a single printing point, a vibrator having ribbon-supporting arms widely spaced thereon for oscillating a ribbon up and down, a stationary support, and a de- 15 vice secured to said stationary support and positioned in front of said arms, said device comprising a type-bar guide to guide the type-bars for centering the types, and a guard having tapered faces to guide the 20 ribbon from interference with the stationary support.

8. In a front-strike typewriting machine, in combination, a platen mounted for case- shifting, type-bars carrying types supported 25 to print at a single printing point, a vibrator having ribbon-supporting arms widely spaced thereon for oscillating a ribbon up and down, a stationary support, and a de- 30 vice secured to said stationary support and positioned in front of said arms, said device comprising a guide to guide the type-bars for centering the types, and a guard extending across the printing line on opposite sides 35 of the printing point and conditioned to reduce the exposed ribbon area between the vibrator arms to avoid the catching of the ribbon on the stationary support.

9. In a front-strike typewriting machine, in combination, a platen mounted for case- 40 shifting, type-bars carrying types supported to print at a single printing point, a vibrator having ribbon-supporting arms widely spaced thereon for oscillating a ribbon up and down, a stationary element and a type- 45 bar-guiding and ribbon-shielding device se- cured to said stationary element and ex- tending in front of said arms, said device comprising a guide-plate to guide the type- bars for centering the types, and a forked 50 member secured to the guide-plate below the printing line and having the free ends of said member extending upwardly on oppo-

site sides of the printing point beyond the lower edge of the ribbon when the latter is in position for typing in the lower field and 55 the platen is shifted to the upper-case position, to prevent the ribbon from catching on the guide-plate and to guide the ribbon to its normal path of movement.

10. In a front-strike typewriting machine, 60 in combination, a platen, type-bars carrying types supported to print at a single printing point, a type-bar guide having upwardly- extending guide-fingers, a passage defined by the fingers for guiding the type-bars and centering the types, a vibrator for oscillating a ribbon located between the platen and the type-bar guide and a guard extending up- 65 wardly from said fingers to shield the rib- 70 bon from interference with the type-bar 75 guide by reducing the exposed area of the ribbon at the printing position.

11. In a front-strike typewriting machine, 75 in combination, a platen, type-bars carrying types supported to print at a single print- 80 ing point, a type-bar guide having a print- 85 ing-point indicating means thereon secured to a fixed part of the machine, guide-fingers extending upwardly over said indicating means, a passage defined by the fingers for 90 guiding the type-bars and centering the types, a vibrator having supporting arms widely spaced thereon for oscillating a rib- 95 bon up and down, and a guard secured to said fingers and extending upwardly therefrom beyond the lower edge of the rib- 100 bon when the latter is in its extreme upper operative position to shield the ribbon from interference and to guide the same to its normal path of movement.

12. In a typewriting machine, the combi- 100 nation of a platen and type-bars therefor, a type-bar-guide in front of the platen and below the typing position thereon, a rib- 95 bon-carrier operable to vibrate a ribbon up and down to cover and uncover the print- 100 ing position, and a ribbon-shield secured to the type-bar-guide in front of the ribbon and provided with tapering ribbon-engaging edges to prevent the ribbon from catching upon said guide during the downward move- ment thereof.

JAMES H. S. BATES.
